UNITED STATES PATENT OFFICE.

FRANK J. VAN COTT, OF UNADILLA, NEW YORK.

SILO-DOOR-FASTENING DEVICE.

1,400,250.

Specification of Letters Patent. Patented Dec. 13, 1921.

Application filed July 31, 1916. Serial No. 112,432.

To all whom it may concern:

Be it known that I, FRANK J. VAN COTT, a citizen of the United States, and resident of Unadilla, in the county of Otsego and State 5 of New York, have invented a certain new and useful Silo-Door-Fastening Device, of which the following is a specification.

The object of my invention is to provide a fastener for silo doors of simple, durable and 10 inexpensive construction.

A further object is to provide a fastening device of such form and shape as to be mounted entirely upon the door or door section without the necessity of fastening any 15 keepers or the like on the door frame, and so arranged that when the door sections are installed the fastening device forms a lock and also a portion of a ladder.

Still a further object is to provide such a 20 fastening device that when attached to one section of a silo door, the door may be securely locked in position without the use of tools or special instruments, and without requiring the use of any separate bolts, nuts, 25 nails or other detachable parts.

Still a further object is to provide such an 30 attachment for fastening silo doors, so constructed and arranged that when the door is installed in position and the fastening device 35 is moved to operative position the lock of the fastening device tends to force the door section downwardly for making a tight joint with the next lower door section, and also draws the door tightly against the door frame for making a tight joint at the side 40 edges of the door.

Still a further object is to provide a fastener expressly adapted for silo doors comprising a transverse member adapted to form 45 the rung of a ladder, and comprising lock devices operatively connected with cranks at opposite ends of the transverse member and extended through suitable keeper members, the parts being so constructed and arranged that a tight joint can be maintained 50 between the door frame and door section regardless of considerable variations in the thickness of the door sections with relation to the door frame.

55 In other words, it is my object to provide a fastener of the kind mentioned adapted to draw the door section tightly against the frame, and to form a tight joint whether the outer surface of the door is flush with the door frame or not, and even though the door

section does not fit exactly in the door opening.

My invention consists in the construction, arrangement and combination of the various parts of the device, whereby the objects contemplated are attained, as hereinafter more fully set forth, pointed out in my claims and illustrated in the accompanying drawings, in which:

Figure 1 shows a front elevation of a portion of a silo having door sections equipped with fastening devices, embodying my invention.

Fig. 2 shows a front elevation of one end of my improved attachment, partly in section.

Fig. 3 shows a side elevation of the same as viewed from the central portion of the silo door section to which the attachment is secured.

Fig. 4 shows a bottom or inverted plan view of the device shown in Fig. 2.

In the accompanying drawings I have used the reference numeral 10 to indicate generally that portion of a silo shown, having the spaced upright door frame members 11 on opposite sides of a vertical door opening and having the door sections 12.

It will be seen in Fig. 4, that the door frame members 11 and the door sections 12 are provided at their side edges with ogee joints. The edges of the door section and door frame might be beveled or otherwise shaped, so that the door section may be drawn tightly against the door frame from the inside.

My improved fastening device comprises for each door section a bail or the like, comprising the central horizontal member 14 having at its ends the right-angled parallel extensions 15. The members 15 have at their extreme ends opposite outwardly extending portions 16.

On the outer surface of each door section, near each side thereof, is what I shall call a retainer member 16^a, comprising a portion, having the form of a hollow shell, the edges of which are designed to rest against the surface of the door section 12.

Extending upwardly and downwardly, respectively, from the opposite edges of the shell are vertical flanges 17 adapted to rest against the door section and to be secured thereto by means of bolts 18 and nuts 19.

The retainer being described, has an in-

75

80

110

inner substantially vertical end wall 20 adjacent to the extension 15. In the end wall 20, approximately at the center thereof from top to bottom and in the edge thereof adjacent to the door section, is a substantially semi-circular slot 21 adapted to rotatably receive the member 16.

In the end wall 20 is a slot 22 located substantially in a vertical plane and curved 10 from the top portion of the end wall 20 outwardly and downwardly, as shown in Fig. 3, to the lower portion of the end wall 20 at the part thereof located farthest from the door section 12. It will be seen that the slot 15 22 forms a guide for the movable locking member, hereinafter more fully described.

In the end of the retaining member shell opposite the end wall 20 is a slot 23, which is wider than the slot 22 and somewhat 20 shorter than the slot 22, and is inclined from its upper end, near the upper portion of the retainer member 16^a, downwardly and outwardly, as shown in Figs. 2 and 4.

The central portion of the body of the retainer 16^a on its under surface has an upwardly extending central rib or shoulder 24, and an opposite downwardly extending rib or shoulder 25. The under surface of the wall of the retainer 16^a is inclined from the 30 line of the rib 24 downwardly and laterally in both directions and from the rib 25 upwardly and laterally in both directions.

I provide a movable locking member comprising a substantially straight bolt 26 extended through the slots 20 and 23, respectively, with its central portion received between the ribs 24 and 25, and adapted to fit substantially against the inner surface of the retainer member 16^a, at the central portion 40 thereof, between the ribs 24 and 25 at all times. On the inner end of the bolt 26 is an eye 27 through which the extension 15 is extended.

At its outer end the bolt 26 is bent in such 45 a way as to be inclined toward the door frame 11 when the door section is installed and the bolt 26 is in substantially horizontal position, as at 28.

Formed on the extreme end of the portion 50 28 is a head 29, the face of which adjacent to the door frame 11 when the door section is installed, is slightly beveled in two directions from a line substantially in its horizontal center.

55 It will be understood that the retainer 16^a and the movable locking bolt 26, at each end of the transverse member 14, are substantially similar in construction.

In the practical use of my improved device one complete device is secured to every 60 door section. The door section 12 is inserted into the door opening from the inside of the silo with the edges of the door section engaging the edges of the door frame for 65 forming the ogee joint, shown in Fig. 4.

It may be noted in this connection that any sort of a joint may be used, wherein the total width of the door section is less at its outer surface than at its inner surface, so that when the door section is drawn into the 70 door opening, its edge, whether beveled in the ordinary way or rabbeted, or of the type shown, will be drawn tightly against the edge of the door frame.

In order to insert the door section into the 75 door opening, the horizontal member should be raised to its position shown by dotted lines in Fig. 2, whereupon the outer end of each movable locking member will be inclined downwardly and outwardly, as shown 80 by dotted lines in said figure, and the upper end thereof will be at the upper end of the slot 22.

The door section having been installed, the horizontal member 14 is swung downwardly, whereupon the extensions 15 will swing the eyes 27 downwardly causing the inner ends of the movable locking bolt 26 to follow the curved guide slot 22 downwardly and outwardly. The central portion 90 of the bolt member 26 of the movable locking member will be retained substantially in the central part of the retainer 16^a, between the ribs 24 and 25, while the outer end of the movable locking bolt having 95 the head 29 will be moved upwardly and toward the door frame 11, following the guide slot 23, and it will be noted that during the downward movement of the horizontal member 14, the bolt 26 will also be 100 rotated to some extent, so that the lower beveled face of the head 29 will be moved to flat faced engagement with the door frame 11 as the head 29 is moved upwardly against the door frame.

105 During the final movement of the parts to locking position, the lower inner face of the head 29 will engage the door frame 11, so that the door section 12 under consideration will be drawn downwardly for engaging a 110 lower door section with its lower edge, forming a tight joint with the next lower door section.

115 It will be noted that when the movable locking member is in its inoperative position, shown by dotted lines in Fig. 2, the head 29 is not only lower than when in its operative position, but that the head 29 is also located inwardly from the frame 11, and within the outline of the door section, and 120 when the entire device is moved to operative position, the head 29 not only is moved upwardly and inwardly toward the door frame, but also moves laterally to a position beyond the edge of the door section; 125 the path of the movement of the head 29 being from the position shown by dotted lines in Fig. 2 to the position shown by full lines in said figure.

130 Many of the advantages of my improved

silo door locking device may be seen from the foregoing description.

Attention is called to the extreme simplicity and cheapness of its structure.

5 The retainer member may be made in the form of an ordinary casing, and it may be cast without making a single core.

The whole device is of comparatively little weight, and yet the retainer member 16^a is

10 so constructed and so supports the movable members, that the entire strength of the retainer member is employed for holding the parts in their locked position.

Attention may be called to the fact also 15 that doors equipped with this locking device may be installed and firmly locked without the use of any wrench or other tool of any kind, and that the use of any bolts, nuts or other detachable parts, is unnecessary.

20 The retainer members and movable locking bolts are so located that when the movable locking members are being moved to their operative locking bolt positions, by swinging the horizontal members 14 down-

25 wardly, the person installing the door section has the advantage of a lever and a wedge whereby the parts may be easily moved to their proper positions for firmly drawing the door section against the frame.

30 The ribs 25 and 24 form fulcrums for the bolt 26, and the slots 22 and 23 form true guides, whereby the movable locking bolt is accurately moved to its various positions.

35 In this connection mention may be made of the peculiar construction, whereby the end of the locking bolt 26 swings upwardly and downwardly between the ribs 24 and 25, and also inwardly and outwardly, and at 40 the same time the bolt 26 rotates slightly and moves longitudinally.

The ribs 25 and 24 are so located that the space immediately between them, when the parts are installed, is below the level of 45 the center of the slot 21, so that when the horizontal member 14 is moved to its lowermost position, the extension 15 will be inclined downwardly and outwardly from the door section, and the bolt member 50 26 may be substantially horizontal, as shown in Fig. 2.

When however, the horizontal member 14 is raised for unlocking the device, it will be noted that the eye 27 not only swings upwardly for moving the locking bolt 26 out of horizontal position, but also follows the extension 15 for sliding the bolt 26 longitudinally, thereby assisting in drawing the head 29 laterally from position overlapping 55 the door frame 11 to position within the outline of the door section 12, while at the same time, the curved slots 22 and 23 cause the inner end of the member 26 to move upwardly toward the door section and the outer

end of the bolt member 26 moves downwardly and away from the door section. 65

There is an advantage in thus having the head 29 spaced from the door section at the beginning of its movement toward locked position in that it is always enabled to properly clear the edge of the frame 11. 70

The eye 27 is of such size as to permit its proper play of the extension 15.

On account of the arrangement of the bolt member 26 with the edges of the slots 22 and 23, the friction of the bolt 26 with said edges is so great that when the parts are in locking position, even though the outer end of the bolt 26 may not be at the extreme end of the slot 23 and the inner end of said bolt may not be at the extreme lower end of the slot 22, yet no tendency of the door to move inwardly due to expansion or contraction or otherwise from within, will move the movable locking member from its operative position, or permit the horizontal member to swing upwardly. 85

It will be noted that the lower end of the slot 22 for a substantial portion of its length is arranged almost in vertical lines, so that 90 the tendency of the door to move inwardly, due to expansion, would only tend to force the inner end of the locking member 26 directly inwardly against the inner edge of the slot 22. 95

Another advantage of my locking device, lies in the arrangement of the inner faces of the head 29 which are so arranged that as the head 29 moves upwardly, and is slightly rotated, it tends to roll slightly against the 100 door frame 11, so that the door frame 11 is not torn or gouged.

It will be noted that the construction of my locking device is such that a tight joint can be made and the door section firmly 105 locked in position even where the outer surface of the door section does not come flush with the outer surface of the door frame. This is important on account of the fact that there is always a slight variation in the 110 width of the door frame in building different silos.

The parts are so arranged and constructed that a tight joint can be made even if the outer surface of the door section should 115 project slightly beyond the outer surface of the door frame.

On account of the construction of the slots 22 and 23, and the ribs 24 and 25, it will be seen that the variations mentioned in the 120 last two paragraphs may occur, and that in any of said variations in the positions of the parts, the members 14 will be in position to serve as a ladder.

Any use of the members 14 as a ladder will 125 not interfere with the locking of the door.

Some changes may be made in the shape and arrangement of the parts of my im-

proved device without departing from the essential features and purposes thereof, and it is my intention to cover by this application any such modified forms of structure or use of mechanical equivalents, as may be included within the reasonable scope of my claims.

I claim as my invention:

1. In a device of the class described, a locking bolt provided with a head, having a surface offset from the locking bolt, a retainer member for said locking bolt having guide and fulcrum portions, and a member operatively connected with said locking bolt, the parts being so arranged that when said last member is operated, said bolt is rotated, slid longitudinally and tilted.

2. In a device of the class described, a door, a retainer member mounted on said door near one edge thereof, a member rotatably mounted in a portion of said retainer having a substantially right-angled extension, said retainer being provided with a pair of slots, a fulcruming device between said slots, a removable locking member extended through said slots and adapted to co-act with said fulcruming device, having one end pivotally and slidably mounted on said extension, and having on its other end a head, the parts being so arranged that when said extension is moved on its pivotal center, said head is moved from position within the outline of the door, and spaced from the door to a position beyond the edge of the adjacent door surface for causing said head to engage a door frame around the door, and drawing the door against such frame, or in an opposite direction, depending upon the direction of movement of said extension.

3. In a device of the class described, a door, a retainer member mounted on said door near one edge thereof, a member rotatably mounted in a portion of said retainer having a substantially right-angled extension, said retainer being provided with a pair of slots, a fulcruming device between said slots, a removable locking member extended through said slots and adapted to coact with said fulcruming device having one end pivotally and slidably mounted on said extension and having on its other end an off-set head, the parts being so arranged that when said extension is moved on its pivotal center, said head is moved from position within the outline of the door and spaced from the door to a position projecting beyond the door outline and toward the extended vertical plane of the adjacent door surface for causing said head to engage a door frame around the door

and draw the door against such frame, or in an opposite direction depending upon the direction of movement of said extension, said head having on its side adjacent to the door bevelled faces, whereby when the locking member is moved to locking position, the

head may roll slightly on an adjacent door frame.

4. In a device of the class described, a door, a retainer member mounted on said door near one edge thereof, a member rotatably mounted in a portion of said retainer having a substantially right-angled extension, said retainer being provided with a pair of curved slots and a fulcruming device, a removable locking member extended through said slots and adapted to coact with said fulcruming device, having one end pivotally and slidably mounted on said extension and having on its other end, a head, the parts being so arranged that when said extension is moved on its pivotal center, said head is moved from position within the outline of the door and spaced from the door, to a position projecting beyond the door outline, and toward the extended vertical plane of the adjacent door surface for causing said head to engage a door frame around the door and draw the door against such frame, or in an opposite direction, depending upon the direction of movement of said extension, the edges of said slots being so inclined as to firmly engage the movable locking member in a variety of its positions, so that any inward or outward pressure of the door will not move the movable locking member from its operative locking position.

5. In a device of the character described adapted to be used in combination with a closure member for silos or the like, comprising a retainer member fixed to the closure member having portions forming spaced guides and portions forming fulcrums, a locking bolt arranged in position to coact with said guides and fulcrums, and means pivotally and slidably connected with said locking bolt for imparting to it sliding and rotary movement.

6. In a device of the character described, the combination of a closure member with a locking bolt, having a head with a surface offset from the bolt, and means for sliding and rotating and for tilting said bolt for swinging its end having the head toward or from the plane of the adjacent surface of the closure member.

7. In a device of the class described, the combination of a closure member with a locking bolt, having an offset head, and means for sliding said bolt for moving it from position within the outline of the closure member to position projecting beyond said outline or vice versa, and for rotating said bolt and for tilting said bolt, whereby it will engage the surface of the silo adjacent to the outline of the closure member, when the parts are in their locking position.

8. In a device of the class described, the combination of a closure member with a movable step or rung member, a locking bolt, having an offset head operatively con-

nected with said step member, and a retainer member having guide and fulcrum portions, whereby the movement of the step member imparts sliding, tilting and rotary movement to said bolt, whereby it will be moved from position within the outline of the closure member to position projecting beyond said outline or vice versa.

9. In a device of the class described, the combination of a closure member with a movable step or rung member, means for pivotally supporting said last member, a locking bolt operatively connected with said step member, and a retainer having guide and fulcrum portions adapted to receive the locking bolt, whereby the movement of said step member operates said bolt for sliding said bolt from position within the outline of the closure member to position projecting beyond said outline and vice versa, and for tilting one end of said bolt toward or from the plane in which the adjacent surface of the closure member lies.

10. In a device of the character described, the combination of a building, having a door opening, a door section for fitting said opening, a step member having its ends pivotally supported on said door section, the ends of said step member being provided with cranks, locking devices slidably and pivotally mounted on the arms of said crank members, and a guide and fulcrum device for each locking device, having members for engaging the locking device, whereby when the step member is swung on its pivot points, said locking devices will be rotated, slid longitudinally and tilted, whereby the locking devices will engage the building adjacent to the door opening.

11. In a device of the class described in combination with a building, having a door opening therein, and a door section adapted to be received within said door opening, retainer members fixed to said door section, and each provided with a guide and fulcrum portion, a locking bolt arranged in position to coact with said guide and fulcrum, a step or rung member pivotally mounted within said retainer members and adapted to coact with one end of the locking devices, whereby movement of the step member upon its pivot points will cause the locking devices to be rotated, slid longitudinally and tilted until the outer or free end of the locking devices is moved from position within the outline of the door section to position outside of the outline of the section member or vice versa.

12. In a device of the class described in combination with a building having a door opening therein, and a door section for fitting said opening, a crank member having its ends pivotally supported on said door section, locking devices pivotally and slidably mounted on the arms of said crank

member, and a guide and fulcrum device for each locking device, having members for engaging the locking devices, whereby when the crank member is swung upon its pivot points, said locking devices will be rotated, moved longitudinally and tilted, so that when the door section is placed in said door opening, and the crank member is swung upon its pivot points in one direction, the outer ends of the locking devices will engage and roll on the frame of the building adjacent to the door opening for locking the door section in place.

13. In a device of the character described adapted to be used in combination with a closure member for silos or the like, comprising a retainer member fixed to the closure member, having portions forming spaced guides, and portions forming fulcrums, a locking bolt arranged in position to coact with said guides and fulcrums, and means pivotally and slidably connected with said locking bolt for imparting to it sliding, tilting and a rotary movement, whereby said locking bolt will be moved to position, where the closure member will be rigidly held in place.

14. In a device of the class described, the combination of a closure member with a movable step or rung member, means for pivotally supporting said last member, a locking bolt operatively connected with said step member and provided with an offset head, and a retainer having guide and fulcrum portions, whereby the movement of said step member operates said bolt for sliding said bolt from position within the outline of the closure member to position projecting beyond said outline and vice versa, and for tilting the end of the bolt provided with the offset head toward the plane in which the adjacent surface of the closure member lies.

15. In a device of the class described in combination with a building, having a door opening therein, and a door section for fitting said opening, locking devices fixed to each side of the door section, the locking devices comprising a retainer member provided with spaced slotted guides, and a fulcrum portion formed between the spaced, slotted guides, a locking bolt adapted to be received in said spaced guides and to extend between said fulcrum portion, the locking bolt being provided with an offset head on one end and a loop on its other end, a movable step or rung member pivotally supported on said retainer member, said step member being provided with crank arms at each end, which are adapted to be slidably received within the loop formed on said locking bolt, whereby movement of said step member upon its pivot points will cause the locking bolt to move within the spaced guides,

whereby it will be rotated, slid longitudinally and tilted until the head portion is moved from position within the outline of the door section or vice versa, the parts 5 being so arranged that the greater movement of the step member in one direction will cause the locking bolt to more firmly engage the frame of the door opening.

16. In a device of the class described, a 10 support, a retainer having spaced curved guide slots and spaced fulcrums between said slots, a pivoted rod, a locking bolt extended through said slots and between said fulcrums having one end slidably mounted 15 on said rod, whereby the swinging movement of the rod, imparts rotary, tilting, sliding movement to the bolt.

17. In a device of the class described, a 20 structure having an opening, a closure member for said opening, a retainer having spaced curved guide slots and spaced fulcrums between said slots, a pivoted rod, a locking bolt extended through said slots and between said fulcrums having one end slidably 25 mounted on said rod, whereby the swinging movement of the rod, imparts rotary, tilting, sliding movement to the bolt for moving the other end of said bolt from position within the outline of the closure member to 30 position projecting beyond said outline and from position in a plane spaced from the structure to position engaging said structure.

18. In a device of the class described, a 35 support, a retainer having spaced guide slots and spaced fulcrums between said slots, a pivoted rod, a locking bolt extended through said slots and between said fulcrums having one end slidably mounted on said rod,

whereby the swinging movement of the rod, 40 imparts movement to the bolt.

19. In a device of the class described, a locking bolt provided with a head, having a surface offset from the locking bolt, a retainer member for said locking bolt having 45 plural guide and plural fulcrum portions and a member operatively connected with said locking bolt, the parts being so arranged that when said last member is operated, said bolt is rotated, slid longitudinally 50 and tilted.

20. In a device of the class described, a support, a retainer having a guide and a fulcrum portion, a locking bolt extended through said guide and fulcrum portion, a step 55 member pivoted in said retainer and so connected with said locking bolt, that movement of the step member will cause the bolt to be moved toward or from the plane of the surface adjacent to the support. 60

21. In a device of the class described, the combination of a door frame and a door element having a step member pivotally mounted on said door, a keeper device mounted on said door, a latch loosely pivoted in said keeper device, said latch having one end loosely retained by said step member at a point spaced away from the pivotal point between said latch and keeper devices whereby the movement of said step will 70 cause one end of said latch to move relative thereto and to move in its pivotal connection in said keeper device for causing the free end of said latch to move toward and from the door frame and also upwardly 75 and downwardly.

Des Moines, Iowa, July 26, 1916.

FRANK J. VAN COTT.
